SWITCH POINT LOCK

Edwin W. Goodaire and George Arnold, Shaker Heights, Ohio, assignors to Cleveland Frog and Crossing Company, Cleveland, Ohio, a partnership composed of George C. Lucas and George W. Balkwill

Application February 8, 1933, Serial No. 655,838

8 Claims. (Cl. 246—448)

This invention relates to an improvement in locking devices for railroad switches, such as for example, a turn-out switch on the main track of a railroad.

5 In a railroad turn-out switch the movable rails or points of the switch are thrown from one position to the other position by means of a throwing device usually designated as a "switch-stand". These "switch-stands" and their operative connections to the switch are designed so that after they are operated, the movable rails or points of the switch are held in the desired position.

Since these "switch-stands" are secured to the ties and project upwardly and above the same 15 they may be damaged by projecting members on passing trains or by being struck by wreckage in the event of an accident near the switch, such as for example, an automobile being struck by a locomotive and thrown against the "switch-stand". The "switch-stand" may be damaged so completely that the switch points are free to move and derailments and serious accidents may result.

An object of the invention is to provide a lock 25 for a railroad switch point which is entirely independent of the "switch-stand" and which will automatically lock the switch for main line or fast traffic.

Another object of the invention is to provide a 30 switch point lock wherein substantially all of the parts of the lock and its actuating mechanism are below the ties and are thus protected thereby, to the end that in the event of an accident adjacent the switch, the likelihood of damage to the 35 switch lock is minimized.

Another object is to provide a switch point lock which is entirely independent of the switch stand or switch throwing mechanism, so that even though the switch stand and mechanism is rendered inoperative the lock will not be affected and the switch points will continue to be held in their proper position.

A further object is to provide a switch point lock in which the parts are symmetrical so that 45 the lock can be installed on either of the head ties of the switch or on either side of the switch depending on the design and location of the switch throwing mechanism.

Another object is to provide a switch point lock 50 wherein the actuating rod during operation of the lock acts as a tension rod irrespective of which side of the switch the lock is installed on, whereby bending of the rod will not affect the functioning of the lock.

55 A further object is to provide a switch point

lock which may be installed readily and with a minimum amount of labor, since all of the parts of the lock are connected to the ties.

Another object is to provide a switch point lock which is of simple construction and may be 60 economically manufactured and which will require a minimum amount of maintenance, since all parts of the lock proper are mounted in one casting.

Further and additional objects and advantages 65 will become apparent during the following detailed description of an embodiment of the invention, which is illustrated in the accompanying drawing wherein:

Fig. 1 is a fragmentary plan view of a railroad 70 track and turn-out switch, showing in full lines the locking device of the present invention mounted in operative position upon one of the head ties and in dot and dash lines said device mounted upon the same head tie in a position to 75 be operated from the opposite side of the switch; this view further shows in dot and dash lines the locking device as it would be mounted in the corresponding positions upon the other head tie;

Fig. 2 is a fragmentary view partly in section 80 and partly in side elevation and is taken substantially on line 2—2 of Fig. 1 and shows one of the movable switch points locked in position against one of the fixed rails of the track;

Fig. 3 is a view similar to Fig. 2, but shows the 85 movable switch point moved away from the fixed rail and the lock released;

Fig. 4 is an enlarged fragmentary view of a portion of the switch point lock, part being shown 90 in side elevation and part in section; and

Fig. 5 is a fragmentary view partly in side elevation and partly in section and shows the switch point lock mounted to be operated from the opposite side of the switch from that shown in Figs. 2 and 3.

95 Referring to the drawing, and particularly to Fig. 1 thereof, the fixed rails of the track are indicated at 10 and the movable switch points or rails are shown at 11 and 12. Since the switch illustrated herein is of standard construction 100 and per se forms no part of the present invention, it will be sufficient to state that the switch points are connected together by tie bars 13 so as to move in unison and that the tie bar 13, located between the head ties 14 and adjacent the ends 105 of the switch points, is connected to an actuating rod 16, which, in turn, is operatively connected with the switch actuating or throwing mechanism indicated diagrammatically at 17 and arranged upon the switch stand 18 secured to the head ties 110

14 at one side of the switch. It will be understood that operation of the switch actuating mechanism serves to move the switch points 11 and 12 from the position in which they are shown in Fig. 1, 5 wherein the straight track switch point 12 is closed and the turn-out switch point 11 open, to the other position wherein switch point 11 is closed and switch point 12 is opened. The switch actuating mechanism may be of any desired construction and there is no need for further reference thereto.

As set forth in the objects, the switch point lock of the present invention is secured to and carried by one or the other of the head ties 14 15 and is located in a protected position substantially entirely beneath the upper faces of said ties and is entirely independent of the switch stand and the switch actuating mechanism.

The switch point lock comprises a latch 30 supported by a casting 23 secured to a latch attaching plate 19 which is a flat plate provided with suitable openings for bolts, lag screws, or other means 20, which secure the plate to the top of one of the head ties and it is further provided 25 adjacent one of its ends with spaced openings 21 for attaching bolts 22 of the latch supporting casting 23.

The casting 23 is provided adjacent its upper side with a longitudinally extending slot 24 having intermediate its ends an enlarged opening and terminating at its lower end in an undercut widened slot 25. The heads of the bolts 22 are passed through the enlargement in the slot 24 and into the undercut widened portion 25, after 35 which they are moved toward the opposite end of the casting whereby the heads of the bolts will engage the casting on opposite sides of the slot 25.

The bolts 22 pass through the openings 21 in the plate 19 and the casting is secured to the plate 40 by means of suitable nuts 26 screwed upon the outer threaded ends of the bolts and holding the heads of the bolts in clamping position within the slot 25. A suitable plate 27 may be positioned over the bolts and beneath the nuts 26, so that 45 when its ends are turned up, as shown in Fig. 4, they will engage one of the flat sides of the nuts and hold the same against rotation.

It will be seen that the casting 23 can be adjusted toward or away from the rail 10 merely by 50 loosening the nuts 26 and sliding the casting inwardly or outwardly as the case may be until it has been properly positioned, whereupon the nuts 26 may again be tightened. A screw 28 may be provided with its inner end engaging one of the bolts 22 to act as a positive fastening to prevent the casting 23 slipping on plate 19 should it be attempted to throw the switch without releasing the lock. The adjustability of the casting is an important feature in that it enables the assembly 55 to be secured to the ties in an approximately correct position, while the casting can be accurately positioned so as to properly locate the head of the latch with respect to the switch point, as will later be explained.

60 The inner end of the casting 23 is provided with a pair of spaced ears 29 forming a bearing bracket for the bell-crank or L-shaped latch lever 30, it being noted that said lever is pivoted at the junction of its arms 31 and 32 between the ears 29 upon a pivot pin 33 extending through said ears and the lever. The arm 31 of the lever is the longer and extends in a substantially horizontal position beneath the fixed rail 10 and is provided at its outer end with an upwardly inclined portion having at the outer end thereof a 65

head 34. The head 34 is provided at its opposite sides with shoulders 35 and 36, while the upper side of the head is curved so that the switch point 12, when the latch is released, may pass over the same and hold the latch in released position without, however, preventing closing movement of the switch point. The arm 32 of the lever is relatively short and extends vertically downwardly and is engaged by a spring plunger 37 slidably mounted in a recess 38 formed in the casting 23 and urged in an outward direction by a spring 39, the tension of which may be adjusted by an adjusting screw 40 mounted in the casting.

The spring pressed plunger 37, as has been stated, engages the arm 32 of the lever 30 and tends to move said arm in a clockwise direction, as viewed in Fig. 4, thus maintaining the head 34 of the lever in the raised or operative position. The outward and inward movement of the plunger 37 is limited by some suitable means, as for example, by means of a pin 41 carried by the casting 23 and engaging in an elongated opening 42 in the plunger. The outward movement of the plunger being limited by the pin, the assembly may be shipped as such without danger of losing 100 the spring and plunger. Since the inward movement of the plunger is limited, as set forth, it will be seen that the plunger also acts as a stop to limit the swinging movement of the lever in a direction to release the latch.

A fork 43 on the end of a rod 44 straddles the lower end of the arm 32 of the lever 30 and is pivotally connected thereto by means of a pivot pin 45 extending through the fork and the arm 32. The opposite end of the rod 44 is provided 110 with a similar fork 43a which straddles a treadle lever 46 and is pivotally connected thereto by means of a pin 47.

The treadle lever 46 is provided with a foot engaging portion 48 and is pivotally connected 115 below the pin 47 and in vertical alignment therewith by means of a pivot pin 49 to the downwardly extending arm 50 of an attaching angle bracket 51 which has its horizontal arm secured to the head tie 14 to which the plate 19 is attached and 120 adjacent to the switch stand 18.

For the purpose of better explaining the construction, the installation, and the operation of the switch point lock, reference will be made to the installation and operation of the device when the same is mounted and used as shown in full lines in Fig. 1. As previously stated, the plate 19 is secured to the upper side of one of the head ties 14 and adjacent to the right-hand fixed track 10. The casting 23 may be assembled on the plate 19 prior to shipment and application of the plate to the ties, or it may be mounted on the plate after the latter has been secured to the ties. The casting 23, if necessary, is then adjusted relatively to the fixed rail 10 until the head 34 of the lever 30 is in such position that the shoulder 35 thereon will engage with the flange of the switch point 12, when said point is against the rail 10, as clearly illustrated in Fig. 2. The bracket 51 is secured to the same head tie 14 but adjacent to the switch stand 18 and in such position that when the latch lever 30 is held by the spring plunger 37 in its operative position, with the shoulder 35 engaging the flange of the switch point 12, the rod 44 will hold the treadle lever 46 135 in its elevated position.

When it is desired to shift the switch points 11 and 12 to the opposite position to that shown in Fig. 1, that is, to the position in which the point 11 will engage with the left-hand fixed rail 10, 140

the switchman depresses the treadle 46 with his foot, whereupon the lever 30 is rocked in an anti-clockwise direction, as viewed in Fig. 2, and the shoulder 35 of the head 34 is disengaged positively

5 from the flange of the switch point 12. The switchman maintaining the treadle depressed then operates the switch actuating mechanism to throw the switch, whereupon the switch point 12 passes over the head 34 of the lever 30 and holds 10 the same in the depressed position. When it is desired to return the switch points 11 and 12 to the position shown in Fig. 1, the switchman merely operates the switch actuating mechanism to this end, but does not have to depress the treadle 46, 15 it being noted that as the switch point 12 rides off of the head of the lever 30, the spring pressed plunger 37 swings the lever in a clockwise direction, as viewed in Figs. 2 and 3 and the shoulder 35 is again brought into locking engagement with 20 the flange of the switch point 12.

The lever 30 is so positioned and the head 34 thereof so dimensioned that when the switch point 12 is moved to the position shown in Fig. 3, there will be no danger of the head 34 swinging 25 in between the fixed rail 10 and the switch point 12, and thus prevent return of the switch point to the position shown in Fig. 2.

If it is desired to mount the switch point lock upon the other head tie 14, it is merely necessary 30 to remove nuts 26, turn casting 23 end for end on plate 19 and then refasten the bolts 22. In like manner the treadle assembly may be transferred to and secured upon the other head tie 14 by first removing pedal 46 from bracket 51, turning it end 35 for end and reassembling on pivot 49.

In case the "switch-stand" 18 is located on the other side of the track, the plate 19 with the casting 23 thereon is secured to one or the other of the head ties 14 intermediate the switch points 11 and 12 and the casting 23 is adjusted so that when the lever 30 is in the raised position, the shoulder 36 of the head 34 engages the flange of the switch point 12, as clearly shown in Fig. 5. The foot treadle 46 is mounted on the head tie in the same way as previously explained, while a longer rod 44 is used to connect the lever 30 with the treadle. In other respects, however, the operation of the switch point lock, when thus mounted, is the same as has been previously explained.

It will be noted that irrespective of the position in which the switch point lock is mounted, the rod 44 operates in tension and not in compression and hence should said rod become bent, the functioning of the lock would not be altered or affected, the result being merely that the treadle 46 would be slightly elevated.

From the foregoing description it will be clearly seen that substantially all of the parts of the switch point locks are located below the level of the head ties and, therefore, in a protected position.

It will further be noted that the switch point lock is entirely independent of the switch stand or the switch actuating mechanism and, therefore, even though such stand or mechanism were destroyed, the lock would not be affected.

It should also be observed that the pivot for the latch lever, the operating spring 39, and the stop 50 which limits the downward movement of the lever when the latch is released are all contained in one casting and, therefore, will require a minimum amount of maintenance.

Although a preferred embodiment of the invention has been illustrated and described herein,

it should be understood that the invention is susceptible of various adaptations and modifications within the scope of the appended claims.

Having thus described our invention, we claim:

1. A lock for railway switch points comprising, 80 means adapted to be secured to a head tie adjacent a fixed rail of the track, a latch pivotally connected to said means and provided with a head adapted to engage a movable switch point to lock the same against the fixed rail, a spring pressed 85 plunger carried by said means for holding said latch normally in locking position, cooperating means on said plunger and said first named means for limiting the movement of said plunger in both directions, and means operable from a point adjacent to the switch stand for positively actuating said latch to unlocking position.

2. A lock for railway switch points comprising, 90 means adapted to be secured to a head tie adjacent a fixed rail of the track, a substantially L-shaped latch lever pivotally connected to said means and having one of its arms provided with a head adapted to engage with a movable switch point to lock the same against the rail, a spring pressed 95 plunger carried by said means and engaging the other arm of the lever to hold said latch lever normally with its head in locking position, and means operable from a point adjacent to the switch stand for positively actuating said lever to move said head to unlocking position.

3. A lock for railway switch points comprising, 100 a plate adapted to be secured to a head tie and adjacent a fixed rail of the track, a member secured to said plate and lying substantially entirely beneath the plane of the upper surface of the tie, said member being adjustable with respect to said plate toward and away from said rail, a latch lever pivotally connected to said member and provided with a head adapted to engage a movable switch point to lock the same against the fixed rail, spring pressed means carried by said member and engaging said latch lever for holding said head normally in locking position, and means operable from a point adjacent to the switch stand for positively actuating 110 said latch lever to move said head to unlocking position.

4. A lock for railway switch points comprising, 115 means adapted to be secured to a head tie adjacent a fixed rail of the track, a latch lever pivotally connected to said means and provided with spaced shoulders adapted to engage a movable switch point to lock the same against the fixed rail whereby the position of said latch lever may be reversed, means for normally holding said 120 lever in locking position, and means operable from a point adjacent to the switch stand for actuating said lever to unlocking position.

5. A lock for railway switch points comprising, 125 an attaching plate adapted to be secured to either head tie and adjacent to either side of a fixed rail of the track, a reversible member secured to said plate and lying substantially entirely beneath the plane of the upper surface of the head tie to which the plate is secured, a latch lever pivotally connected to said member and provided with a portion adapted to engage a movable switch point to lock the same against a fixed rail, means for holding said portion of said lever normally in locking position, and means operable from a point adjacent to the switch stand for actuating said latch to move said portion to unlocking position.

6. A lock for railway switch points comprising, 140 a plate adapted to be secured to either head tie 145

and adjacent to either side of a fixed rail of the track, a member secured to said plate and lying substantially entirely beneath the plane of the upper surface of the tie, said member being reversible with respect to said plate and adjustable toward and away from said rail, a latch lever pivotally connected to said member and provided with a portion adapted to engage a movable switch point to lock the same against the fixed rail, means for holding said portion of said latch lever normally in locking position, and means operable from a point adjacent to the switch stand for actuating said latch lever to move said portion to unlocking position.

15 7. A lock for railway switch points comprising, a plate adapted to be secured to either head tie and adjacent to either side of a fixed rail of the track, a member having a latch lever pivotally connected thereto, means for adjustably and reversibly securing said member to said plate and substantially entirely beneath the upper surface of the head tie, said latch lever having a head provided with oppositely disposed spaced shoulders adapted to engage a movable switch point to lock

25

the same against the switch rail whereby said latch lever and said member may be selectively positioned on either side of the fixed rail, means for holding said latch lever normally in locking position, and means operable from a point adjacent to the switch stand for actuating said lever to unlocking position.

8. A lock for railway switch points comprising, a member adapted to be connected with either head tie and adjacent to either side of a fixed rail of a track and lying substantially entirely beneath the plane of the upper surface of the head tie with which it is connected, means associated with said member whereby its position may be reversed, a latch lever pivotally connected to said member and provided with a portion adapted to engage a movable switch point to lock the same against a fixed rail, means for holding said portion of said lever normally in locking position, and means operable from a point adjacent to the switch stand for actuating said latch to move said portion to unlocking position.
